PHONOGRAPH CARTRIDGE

Jay S. Waxman, Skokie, and Lester A. Miller, Prospect Heights, Ill., assignors to Shure Brothers Incorporated, a corporation of Illinois

Filed Sept. 21, 1961, Ser. No. 66,797

Term of patent 14 years

(Cl. D26—14)

FIGURE 1 is a top plan view of a phonograph cartridge embodying my new design;

FIGURE 2 is a side elevational view;

FIGURE 3 is a bottom plan view;

FIGURE 4 is a front elevational view; and

FIGURE 5 is a rear elevational view.

The opposite side from that shown in FIGURE 2 is substantially identical in design and appearance to that shown in FIGURE 2.

We claim:

The ornamental design for a phonograph cartridge, substantially as shown and described.
